SHIELDING FOR RADIO-FREQUENCY AMPLIFIERS

Application filed December 24, 1927. Serial No. 242,344.

This invention has to do with vacuum tube circuits and relates more especially to high-frequency amplifiers in radio receiving sets.

In order to utilize multistage tuned radio-frequency amplification to the best advantage it is necessary to magnetically and electrostatically segregate the several tuned stages from each other either by wide separation, which is disadvantageous, or by

means of metal shielding.

Where shielding has been employed heretofore it has been the practice to enclose all the apparatus of each tuned radio-frequency stage within an individual metal compartment—preferably copper or aluminum. These metals are employed for that purpose on account of their high conductivity and adaptability, and further, because they are the least expensive of the metals which are electrically suitable. Such shielding, however, is comparatively expensive because of the exacting workmanship required. In order to screen effectively closely adjacent high-frequency stages from each other and prevent all undesirable magnetic and electrostatic interaction between them, it is essential that all seams in the shielding be tightly closed and preferably soldered, that such openings as are necessary to provide access to the compartments be tightly closed, and that holes for the wiring to pass through shall be as small as possible. Shielding, such as that referred to, in the form of copper or aluminum compartments when properly constructed is entirely satisfactory but expensive.

The present trend is toward production in large volume of radio receiving sets which are both highly efficient and inexpensive, and the successful accomplishment of such an undertaking is dependent upon the manufacturer's ability to eliminate every non-essential item in so far as it is possible to do so without detriment to the essential qualities of the product. In line with this endeavor, the object of the present invention is to provide metal shielding which is less expensive than that heretofore employed by equally, or at least, sufficiently, effective.

In accordance with the present invention

it has been found that very effective inter-stage shielding may be obtained by the provision of individual shields for the radio-frequency coupling transformers in the form of copper or aluminum tubes of slightly 55 larger physical dimensions than the transformers. These shielding tubes encircle, or enclose the transformers except at the ends, thereby restricting their respective magnetic and electrostatic fields and effectively prevent interaction between the transformers.

By virtue of the excellent shielding properties of the tubular metal shields, the coupling transformers of a multistage radio receiver may be located closely adjacent each 65 other and, if desired, with their magnetic axes parallel, without fear of interaction.

In some cases, however, where the radio-frequency amplification is extraordinarily high, experience has indicated that it is 70 sometimes desirable to provide supplemental shielding of the compartment type, segregating the several radio-frequency stages of the receiver from each other. Such supplemental shielding may be made of the 75 less expensive metals, as for example, iron, or even brass or zinc—which metals have heretofore been found impracticable for this purpose because of their high specific resistances and the consequent introduction of 80 excessive losses in the coupling transformers. Such additional shielding has, however, little or no effect upon the electrical characteristics of the coupling transformers where the tubular shields as herein described 85 are also employed. This is primarily because of the fact that the major portion of the magnetic field of each stage is confined by the tubular shield surrounding the transformer, leaving only the magnetic field resulting from the wires connecting the transformers with their associated apparatus, and the electro-static fields of said apparatus. The magnitudes of these remaining fields are relatively very small; hence it has been 90 found unnecessary in many instances to exercise great care in the construction of such supplemental shielding. That is to say, the joints may be riveted or crimped instead of 95 soldered at the points of contact, and the 100

seals do not have to be made especially tight. For the same reason other expensive operations may be partially or totally eliminated.

In addition to the saving which may be realized on the cost of the shielding itself, the invention is adapted to bring about further manufacturing economies and mechanical and electrical advantages resulting from simplified construction. This applies particularly to the arrangement herein described for mounting the radio-frequency transformers and for bonding the shields to each other.

In the accompanying drawings, Figs. 1 and 2 are plan and side views, respectively, of a unit comprising three radio-frequency transformers together with their respective tubular shields;

Fig. 3 is a cross-sectional view taken along line 3—3 of Fig. 1;

Figs. 4 and 5 are side and end views, respectively, of an alternative form of shield which may be substituted for the form shown in Figs. 1, 2 and 3;

Fig. 6 is a plan view, and Fig. 7 an end view illustrating shielding of the rectangular compartment type which may be used in conjunction with the tubular shields.

It is to be understood that the apparatus illustrated in the drawings and to be described herein is intended to form a part of a high-frequency vacuum tube amplifier of the tuned multistage type, and especially amplifiers for use in radio receivers. High-frequency amplifiers are, of course, used for other purposes than that of radio reception, and the invention is not to be construed as limited to radio receivers, although that now appears to be its most important application.

In Figs. 1, 2 and 3 there is shown an assemblage of three radio-frequency coupling transformers 1, 2 and 3, respectively. These transformers are of the usual cylindrical form comprising a core of dielectric material upon which the primary and secondary coils are wound. Each of the transformers is partly enclosed within a metal shielding tube 4, 5 and 6, respectively. These tubes may be of circular, square or polygonal cross-section and are usually made of copper or aluminum on account of the desirable electrical qualities of these metals—particularly their high conductivity. The shielding tubes are made with an inside diameter somewhat greater than the outside diameter of the transformers which they encircle and their length is preferably such that they overlap, or extend beyond the transformer windings at both ends. In keeping with the object of the invention the metal tubes are preferably made as small as the controlling conditions will permit. Experience has indicated that the dimensions of the shielding tubes are not highly critical. If, how-

ever, the clearance between the transformer windings and the inside surface of the surrounding tube is too small the distributed capacity of the coil will be measurably increased and is apt to be excessive.

Some typical examples of transformer and shielding tube dimensions which have been found to be entirely satisfactory will now be given. In the first example, the tubular transformer core is $1\frac{1}{4}$ inches outside diameter and $2\frac{1}{8}$ inches long. The tubular shields for that particular transformer are $2\frac{1}{4}$ inches in diameter inside and $2\frac{3}{4}$ inches long. The primary winding in that example comprises $19\frac{2}{3}$ turns of No. 36 double silk covered copper wire, and the secondary winding comprises 120 turns of No. 30 enameled wire. The radial clearance in that case between the windings and the inside of the shielding tube is approximately $\frac{1}{2}$ inch. The tubular shield in that case overlaps the ends of the windings about $\frac{1}{2}$ inch at each end. In another case, the tubular transformer core is $2\frac{1}{4}$ inches outside diameter and 2 inches long. The tubular shield has an inside diameter of $3\frac{1}{4}$ inches and is $2\frac{1}{2}$ inches long. The primary winding in the latter case comprises $13\frac{1}{4}$ turns of No. 36 double silk covered copper wire and the secondary winding 70 turns of No. 28 enameled wire. As in the previous case the radial clearance between the winding and the inside of the tubular shield is approximately $\frac{1}{2}$ inch and the overlap at the ends is about $\frac{1}{2}$ inch in each instance. The foregoing dimensions are given purely as examples and are not to be regarded as in any way limiting.

In the structure of Figs. 1, 2 and 3, the three tubular shields 4, 5 and 6 are illustrated as being riveted together along their lines of contact, and may conveniently be fastened in like manner to a supporting base. This form of construction is not only a manufacturing convenience, but results in mechanical and electrical advantages. For example, after the tubular shields have been fastened together mechanically the entire coil assembly, including the shields, is a structurally rigid unit which can easily be handled as such in the factory. Furthermore, the structure is sufficiently strong to support additional apparatus on the top thereof, if required, as when the structure is placed in a radio set with the axes of the coils horizontal, as shown in the figures. As to an important electrical advantage, it will be evident that when the adjacent shields are secured together with good electrical connection, the electrical path from one end to the other through the shields as a whole will be of extremely high conductivity since, as already pointed out, the tubular shields are preferably constructed of copper. Thus when one or more of the wind-

ings of each coil is electrically connected directly to its respective shield, as is now customary in the art, the entire tubular shield structure will serve as a common return or ground lead of such low electrical resistance as to introduce practically no undesirable interstage couplings due to a "high impedance ground".

For the purpose of supporting the transformers there is provided a strip 7 of suitable insulating material. This strip is fastened to the shielding tubes by means of a number of small brass clips 8 one end of each of which is welded, soldered or riveted to one of the tubular shields. The clips 8 project through holes provided in the strip 7 and are bent down, as shown in Fig. 1, thereby securing the strips 7 in place. The transformers 1, 2 and 3 are in turn fastened to the strip of insulating material 7 by means of metal clips 9 similar to those indicated by reference numeral 8. The clips 9 are each riveted at one end to a transformer core and pass through openings provided in the supporting strip 7 and are bent over, as shown in Fig. 1. The clips 9 may be made to serve as soldering terminals for the transformer windings, thereby effecting an additional economy. This arrangement for supporting the transformers and centering them within the tubular shields provides a very inexpensive form of construction and greatly expedites the assembling operation.

Figs. 4 and 5 illustrate an alternative form of shielding which is slightly cheaper than that previously described, and frequently more advantageous both electrically and mechanically. By reference to Fig. 4 it will be seen that the tubular shields are made of two identical half-portions 10 and 11, respectively, each formed with three semi-circular sections. The two half-portions are preferably welded or soldered together along their lines and surfaces of contact, which in this case comprises a flat portion or web 14, whereby there are obtained the same mechanical and electrical advantages previously described in connection with the structure of Figs. 1, 2 and 3. Furthermore, the use of this form of shield usually results in somewhat improved electrical characteristics because a permanent and highly conductive connection between the semi-circular sections may readily be obtained. The transformers 55 may be attached to the shields of Figs. 4 and 5 in the same manner as illustrated in Figs. 1, 2 and 3.

Where the radio-frequency amplification is unusually high and it becomes necessary to provide additional shielding, an arrangement such as that illustrated by Figs. 6 and 7 may be utilized to advantage. The latter figures illustrate a metallic housing 12 having three compartments in each of which 65 is enclosed all the high-frequency apparatus

of an amplifier stage. Within each of the compartments there is contained a tubular shield 13 encircling the radio-frequency coupling transformer in the manner illustrated in Figs. 4 and 5. The Fig. 4 type of shield is frequently advantageous in connection with a radio-frequency amplifier such as that illustrated in Figs. 6 and 7 because the flat portion or web 14 serves to link the shields together and may be made of any length desired; thus resulting in the desired spacing between the individual coils. The top view of the radio-frequency amplifier of Fig. 6 illustrates the use of such spacing. The housing 12 is of the usual form of rectangular compartment shield except that it may be made of iron or some other type of inexpensive metal, and need not be constructed so precisely as the ordinary copper shielding heretofore in use. Shielding of 85 this type made of iron would not be at all satisfactory in the absence of the highly conductive inner shielding herein described. That is true even though care be exercised to insure all the seams being made tight. Without the highly conductive shields, the losses which would ordinarily be introduced by iron shields would be altogether excessive; but when the highly conductive shields are used in combination with the slightly conductive iron shields, as illustrated in Figs. 6 and 7, it is found that the losses are negligible, while the screening or shielding effect is all that could be desired.

It appears that the open-ended tubular metal shields are fully effective to prevent magnetic and electrostatic coupling between the transformers, but where the amplification is unusually high there is likely to be some undesirable interstage magnetic and electrostatic coupling between the leads and connected components which extend beyond the tubular shields. Apparently it is only coupling of the latter character, (i. e. between leads, etc.) that the iron compartment shielding is required to prevent, and since this is of comparatively small magnitude the iron shielding does not need to be very precise; nor is it of any practical consequence that the iron introduces some small hysteresis losses.

No details of construction of the housing 12 have been shown because such construction is within the ordinary skill of sheet metal workers.

It should be clear from Figs. 6 and 7 that the coupling transformers 1, 2 and 3, tuned by variable condensers 15, 16 and 17, couple successive vacuum tubes arranged in cascade in the usual manner; or, alternatively, one of them may be utilized to couple the input circuit of a vacuum tube with an antenna circuit, all of which may be readily understood without the necessity of resorting to further illustrations.

Although the present invention has been described as applied to a transformer-coupled radio-frequency amplifier, it may be applied with equal effectiveness in ways different from that herein specifically described. For example, the tubular metal shields may, under certain conditions, be usefully employed for shielding radio-frequency inductance coils as distinguished from 10 transformers, per se.

We claim:

1. In an amplifier, a plurality of stages of radio-frequency amplification, each stage including a coupling coil, and an open-ended fixed tubular metallic shield encircling said coil and effective to restrict the magnetic field thereof.
2. In an amplifier, a plurality of stages of radio-frequency amplification, each stage including a coupling coil, and an open-ended fixed tubular shield of metal of high conductivity surrounding said coil, said shields functioning to reduce undesirable magnetic coupling between said coils.
3. In an amplifier, a plurality of stages of radio-frequency amplification, each stage including a coupling transformer, and a fixed tubular metal shield open at both ends encircling said transformer and extending a substantial distance beyond the windings of said transformer at both ends, said shields functioning to reduce undesirable magnetic coupling between said coils.
4. In an amplifier, a plurality of high-frequency coupling transformers of the conventional cylindrical type, each of said transformers being provided with an open-ended fixed tubular metal shield of high conductivity, said shields encircling their 40 respectively associated transformers and being of substantially larger inside diameter than the outside diameter of their associated transformers, said shields substantially overlapping the windings of their associated transformers at both ends.
5. In an amplifier, a plurality of stages of radio-frequency amplification, each of said stages including a radio-frequency coupling transformer and other apparatus, an open-ended tubular metallic shield of high conductivity for each of said transformers, each of said tubular shields encircling its associated transformer and extending at each end beyond the windings of said transformer, and supplemental shielding comprising a plurality of compartments in each of which is enclosed the high-frequency apparatus of one of said stages.
6. In a radio-frequency amplifier, a plurality of coupling transformers and a plurality of open-ended tubular metal shields, each encircling one of said transformers and functioning to restrict the magnetic field thereof so as to reduce undesirable coupling 65 between said transformers, said shields be-

ing disposed in parallel side-by-side relation and fastened together along their lines of contact.

7. In an amplifier, a plurality of high-frequency coupling transformers of the conventional cylindrical type, and a plurality of highly conductive fixed tubular metal shields open at both ends, each shield encircling one of said transformers and extending at both ends a substantial distance beyond the transformer windings, whereby undesirable magnetic coupling between said 75 transformers is considerably reduced.

8. In an amplifier, a plurality of stages of radio-frequency amplification, each of said stages including radio-frequency coupling means including a coil, a metallic shield of high conductivity surrounding each of said coils and extending beyond each end thereof, said shields being mechanically and electrically connected along their adjacent surfaces, and supplemental shielding of low conductivity comprising a plurality of compartments in each of which one of 80 said stages is enclosed.

9. In an amplifier, a plurality of stages of radio-frequency amplification, each of said stages comprising a vacuum tube and radio-frequency coupling means including a coil, said coil being surrounded by an open-ended highly conductive metallic shield extending at each end beyond said coil, and supplemental shielding of low conductivity comprising a plurality of compartments in 85 each of which one of said stages is enclosed.

10. In an amplifier, a plurality of stages of radio-frequency amplification, each of said stages including radio-frequency coupling means including a coil, said coil being surrounded by an open-ended metallic shield extending at each end beyond said coil, and supplemental shielding means enclosing a plurality of said first-mentioned shields.

11. In an amplifier, a plurality of stages of radio-frequency amplification, each of said stages comprising radio-frequency coupling means including a coil, a metallic shield of high conductivity for each of said coils, each of said shields having open ends 110 and enclosing its associated coil and extending at each end beyond said coil, and supplemental shielding means of low conductivity relative to said first-named shields comprising a plurality of compartments in each 115 of which one of said stages is enclosed, whereby the effectiveness of shielding is maintained in proportion to the ratio of the tendency towards undesired coupling.

12. In an amplifier, a plurality of stages of radio-frequency amplification, each of said stages comprising radio-frequency coupling means including a coil, a metallic shield of high conductivity having open ends 120 and enclosing each of said coils, and supple- 125

mental shielding means of relatively low conductivity enclosing a plurality of said first-mentioned shields, whereby the undesired transfer of energy between stages is reduced in proportion to the ratio of unrestricted coupling.

13. In an amplifier, a plurality of stages of radio-frequency amplification, each of said stages including a radio-frequency coupling transformer, a plurality of shielding structures each comprising a plurality of semi-tubular portions, a web member between said portions, said shielding structures being electrically and mechanically united to form open-ended tubular enclosures around each of said radio-frequency coupling transformers, whereby the magnetic field of each of said transformers is restricted.

14. The combination, with a multistage radio-frequency amplifier, each stage including a coupling coil, of a shielding structure for said coils comprising a plurality of tubular metallic shields of high conductivity, said shields being disposed in parallel contiguous relation and securely fastened together along their lines of contact, whereby said shielding structure is mechanically strengthened and the radio-frequency conductivity between the extremities thereof is increased.

15. A radio-frequency shielding structure formed from two sheets of metal into complementary halves, each half comprising a row of semi-tubes, said halves being mechanically and electrically bonded along their lines of contact, each tube being adapted to enclose one or more radio-frequency coils.

16. A shielding structure according to claim 15 wherein the halves are formed with a web member between the semi-tubes, whereby the required separation between adjacent tubes is obtained while maintaining high intershield conductivity.

In testimony whereof we affix our signatures.
